FENDER LAMP HOUSING

Vernon L. Neunaber, Santa Ana, Calif.

Application July 9, 1951, Serial No. 15,804

Term of patent 14 years

(Cl. D48—32)

To all whom it may concern:

Be it known that I, Vernon L. Neunaber, a citizen of the United States, residing in the city of Santa Ana, in the county of Orange and State of California, have invented a new, original, and ornamental Design for a Fender Lamp Housing, of which the following is a specification, reference being had to the accompanying drawing forming part thereof.

Fig. 1 is a top plan view of a fender lamp housing, showing my new design.

Fig. 2 is a side elevation thereof.

Fig. 3 is a right hand elevation view of Fig. 2.

Fig. 4 is a bottom plan view.

Fig. 5 is a section on zig-zag line 5—5 of Fig. 2, and

Fig. 6 is a perspective view on a smaller scale.

I claim:

The ornamental design for a fender lamp housing, substantially as shown.

VERNON L. NEUNABER.
